Patented Oct. 24, 1961

191,616

COIN OPERATED AMUSEMENT RIDE

David H. Braun, 950 W. 20th St., Hialeah, Fla.

Filed Mar. 2, 1961, Ser. No. 64,147

Term of patent 7 years

(Cl. D34—5)

FIGURE 2 is a perspective view of the same from the opposite side and,

The dominant features of my design are shown in full lines.

I claim:

The ornamental design for a coin operated amusement ride, as shown and described.
